COCKTAIL PICK

Enrico R. La Barbera, 4220 Aberfoil Ave.,
Oakland, Calif. 94605

Filed Aug. 28, 1964, Ser. No. 81,494

Term of patent 14 years

(Cl. D44—29)

I claim:

The ornamental design for a cocktail pick, substantially as shown and described.
